Primary Examiner — Cynthia R Underwood(74) *Attorney, Agent, or Firm* — Sheridan Ross P.C.(57) **CLAIM**

We claim the ornamental design for a cable management tray, as shown and described.

DESCRIPTION

FIG. 1 is a top front perspective view of a cable management tray;

FIG. 2 is a bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings illustrate portions of the cable management tray, which form no part of the claimed design.

1 Claim, 5 Drawing Sheets(56)
